UNITED STATES PATENT OFFICE.

WILLIAM S. DIMMOCK AND WALTER E. CHRISTIAN, OF CHICAGO, ILLINOIS.

CHECK-CONTROLLED APPARATUS FOR VENDING-MACHINES.

1,250,814.

Specification of Letters Patent.

Patented Dec. 18, 1917.

Application filed January 23, 1917. Serial No. 143,978.

To all whom it may concern:

Be it known that we, WILLIAM S. DIMMOCK and WALTER E. CHRISTIAN, citizens of the United States, residing at Chicago, in the county of Cook and State of Illinois, have invented certain new and useful Improvements in Check-Controlled Apparatus for Vending-Machines, and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in coin-actuated vending mechanism and consists specifically in the provision of a rotatable coin wheel into which the coins are dropped, an oscillating member being provided for actuation to cause the wheels to make a partial rotary movement, thus operating the delivery mechanism.

Our invention comprises a simple and efficient apparatus of this nature having various details of construction, combinations and arrangements of parts which will be hereinafter fully described, shown in the accompanying drawings and then specifically defined in the appended claim.

Our invention is illustrated in the accompanying drawings, in which:—

Figure 1 is a vertical sectional view through a portion of a coin controlled vending machine, showing parts of the invention in elevation.

Fig. 2 is a horizontal cross section showing in top plan view the mechanism illustrated in Fig. 1.

Reference now being had to the details of the drawings by numeral, 1 designates the vending boxing or casing within which is a removable frame 2* in which is journaled a shaft 2, and 3 is a coin wheel which is fixed to the shaft 2 through the medium of the set screw 4. Said wheel has an annular slot in its circumference and has lugs 5 projecting from the walls thereof, dividing the annular slot into compartments, each of a suitable size to receive a coin 6 which is deposited therein through the coin chute 7. 8 designates a bail-shaped member which is journaled upon the shaft 2 and has an offset 9 in one side thereof, as shown clearly in

Fig. 2 of the drawings, and to which one end of the coiled spring 10 is connected, the other end being fastened to a bracket arm 11 secured to the frame 2*. One side of the bail-shaped member 8 has a laterally projecting lug 13, and 14 is a push rod having a longitudinal movement in a contracted portion 15 of the shell 16, and 17 designates a head to said push rod and which is movable within the enlarged portion of the shell 16, and, when at its outer limit, a portion thereof only projects through the front wall of the box. Said bail-shaped member 8 has a laterally extending wing 18 which is curved and which extends over the coin wheel and which is provided for the purpose of supporting a second coin should it be dropped into the slot of the machine before the previously deposited coin has been utilized in connection with the bail-shaped member to give a partial rotary movement to the coin wheel.

One edge of the frame 2* has a lug 19 struck up from the edge thereof, and one end of the bail-shaped member is laterally bent as at 20 and is adapted to contact with the lug 19 to limit the tilting movement of the bail-shaped member in one direction.

The operation of our invention will be readily understood and is as follows:— A coin is dropped through the slot 7 into one of the compartments of the coin wheel and, when therein a portion of the coin will project beyond the circumference of the wheel 3. The machine is now in readiness to be actuated for the purpose of delivering an article when the operator pushes in upon the head 17. This will cause the stem 14 to contact with the lug 13 and a further inward push upon the head 17 will cause the bail-shaped member to assume the position shown in dotted lines in Fig. 1. As its upper end, which extends over the coin wheel, comes in contact with the edge of the projecting portion of the coin, it will cause the coin to impinge against one of the lugs 5 and impart a partial rotary movement to the wheel 3. This in turn will impart a partial rotary movement to the shaft 2 upon which the coin delivery mechanism, not shown, is mounted and which will cause the article to be delivered. In the event of a coin being dropped in the chute after a rotary movement has been imparted to the wheel in the direction shown by arrow in Fig. 1, the coin will drop upon either

the portion which extends over the coin wheel on the lug or the wing 18 and which will tend to support the coin until the bail-shaped member has returned approximately 5 to its normal starting position, after which the coin will drop into the slot in the wheel and the apparatus is reset.

What we claim to be new is:—

A check-controlled apparatus for vending machines, comprising a frame, a shaft journaled therein and designed for actuating delivery mechanism, a compartment coin wheel fixed to the shaft, a spring-actuated, oscillating bail-shaped member journaled 10 upon said shaft and having portions extending over the edges of said wheel at points diagonally opposite, one side of the member

having an offset, an angled finger fixed to the frame and a coiled spring fastened at one end to said offset and the other end to 20 said finger, a push rod mounted within the frame, and a lug projecting from said member below the offset and positioned in the path of said push rod, a portion of the bail-shaped member having a link extending 25 over the edge of the wheel.

In testimony whereof we hereunto affix our signatures in presence of two witnesses.

W. S. DIMMOCK.
WALTER E. CHRISTIAN.
